Primary Examiner — Ricky Pham(74) *Attorney, Agent, or Firm* — Dilworth IP, LLC(57) **CLAIM**

The ornamental design for a toaster, as shown and described.

DESCRIPTION

FIG. 1 is a perspective view of the present design.

FIG. 2 is a front view of the present design.

FIG. 3 is a rear view of the present design.

FIG. 4 is a left side view of the present design.

FIG. 5 is a right side view of the present design.

FIG. 6 is a top view of the present design.

FIG. 7 is a bottom view of the present design.

FIG. 8 is a perspective view of the use state of the present design in an open state.

FIG. 9 is a perspective view of the use state of heating the material in the open state of the present design; and,

FIG. 10 is a perspective view of the use state of heating the material in the folded state of the present design.

The broken lines depict environmental structure that form no part of the claim.

1 Claim, 6 Drawing Sheets(56)
